UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

SOUND-RECORDING APPARATUS.

1,420,317.

Specification of Letters Patent. Patented June 20, 1922.

Application filed November 30, 1914, Serial No. 874,672. Renewed December 16, 1920. Serial No. 431,275.

To all whom it may concern:

Be it known that I, NEWMAN H. HOLLAND, a subject of the King of Great Britain, and a resident of West Orange, in the county 5 of Essex and State of New Jersey, have invented certain new and useful Improvements in Sound-Recording Apparatus, of which the following is a description.

My invention relates to sound recording 10 apparatus, and more particularly to new and improved apparatus for recording telephonic conversations, as upon a phonograph or sound record. One of the objects of my invention is to provide an improved device of 15 this character adapted to be readily used in connection with the ordinary telephones and phonographs in common use and without the necessity of making objectionable connections to the telephone line. Other objects of 20 my invention will appear more fully in the following specification and appended claims:

In order that my invention may be more clearly understood, attention is hereby directed to the accompanying drawings forming part of this specification and in which—

Fig. 1 is a perspective view illustrating the preferred embodiment of my invention:

Fig. 1^a is a perspective view of a telephone outfit adapted to be used in connection with 30 my invention;

Fig. 2 is a diagrammatic view illustrating my invention; and

Fig. 3 is a view partly in section and partly in elevation illustrating certain features of my invention.

In all of the views, like parts are designated by the same reference numerals.

Referring to the drawings the numeral 1 designates a phonograph of the Edison type 40 having a sound recorder 2 mounted in a traveling arm 3 which is slidable along rods 4 and 5 so as to cause the recorder 2 to be carried along the record cylinder or blank 6. The arm 3 has secured thereto a spring 45 support 7 for a feed nut 8 engaging the rotatable feed screw 9 to effect the feeding movement of the arm 3 and the recorder 2 longitudinally of the record. Referring to Fig. 3, the drive pulley 10 is arranged to be 50 rotated from the phonograph motor (not shown) as by a belt 10'. The rotation of the pulley 10 is adapted to be transmitted to the mandrel or support 11 for the cylinder 6 through a shiftable clutch member 12. 55 Movement of the clutch member in one di-

rection or the other serves to connect or disconnect the pulley 10 and the shaft 13 of the support 11. The means shown for controlling the position of the clutch member 12 and thereby starting or stopping the rotation of the support 11 and the cylinder carried thereby comprises a bell crank lever 14 having a loose connection with the clutch member 12, a link 15 connected at one end to the lever 14 and at the opposite end to a lever 65 16, and a suitable pneumatic device connected to the lever 16. The pneumatic device preferably consists of a pump 17 secured to the bottom of the top plate 18 of the phonograph motor cabinet, a second pump 19, and 70 means connecting the said pumps comprising a flexible tube 20 having at its opposite ends members 20' and 20² detachably and frictionally connected to the tubular members 21 and 22 leading to the interiors 75 of the cylinders of the pumps 17 and 19 respectively. The piston 23 of the pump 17 is connected to the lever 16 by a link 24 which is pivotally connected to the piston 23 at one end and to the link 16 at the other end. A 80 limited amount of relative movement between the pump mechanism and the clutch is provided for by arranging the pivot 25 between the lever 16 and the link 24 in a short slot 26 in the link 24. The lever 16 is provided 85 with laterally extending arms 27 and 28 respectively to which are pivotally connected push buttons 29 and 30 respectively which may be alternately depressed by the fingers to effect the shifting of the clutch 12 and 90 the starting and stopping of the rotation of the record cylinder. The numeral 31 designates an ordinary telephone standard 95 carrying a telephone transmitter 32 and a telephone receiver 33. The parts hereinbefore specifically described are of well-known construction and do not per se form any part of my present invention.

The pump 19 hereinbefore referred to is carried on the under side of the top of a 100 box or container 34, which, as will herein-after appear, supports or contains in compact and conveniently arranged manner substantially all of the parts needed to adapt the ordinary recording phonograph for 105 recording the telephone conversations or other sounds transmitted over an ordinary telephone line. The box or container 34, together with the parts carried thereby may be made comparatively light and small so 110

that it may be readily carried around from place to place. The top wall of the said box is provided on the outside with a plurality of arms 35 extending radially from a tubular member 36 which passes through the said wall. The top of the member 36 is preferably rounded off, as shown in Fig. 2, and this member is preferably, though not necessarily, made of soft rubber or other suitable flexible material. The arms 35 may be secured in position by screws *a* or in any other suitable way. The outer ends of said arms are directed upwardly, the upwardly directed portions having inwardly curved portions 35' adapted to engage over the bead or projection 33' on the ordinary telephone receiver so as to hold the said receiver firmly in operative position on the box or container 34 with the diaphragm 33' in direct communication with the interior of the member 36. The member 36 communicates with and extends within the upper portion of a right angular tube 37 which is fastened at its upper end to the top of the box or container 34. The other end of the tube 37 contains the neck 38 of a telephone transmitter 39 which is supported by the tube 37 in the interior of the box or container 34, as shown in Fig. 3.

The telephone transmitter, as shown, comprises a vibratory diaphragm 40 which constitutes one of the electrodes and a plunger 41 adapted to reciprocate in the sleeve 42 and constituting the other electrode, a spring 43 serving to press the electrode 41 against the granular conductive material 44 which lies between the electrodes and to prevent vibration of the electrode 41 by the vibrations of the diaphragm 40. A cylindrical flexible sleeve 45 surrounding and secured to the electrode 41 serves to prevent the granular material 44 from falling out of place between the two electrodes. The transmitter 39 may, if desired, be constructed in the manner set forth in my copending application, Serial No. 767,261 filed May 13, 1913, on which Patent No. 1,226,886 was granted May 22, 1917.

The transmitter 39 is electrically connected, in a manner which will be herein-after more fully set forth, to a telephone receiver 46 and a second telephone receiver 47 mounted upon the neck of the recorder 2 so as to cause said recorder to record upon the record cylinder 6 the vibrations or undulations set up by the transmitter 39. The receiver 47 and the recorder 2 as combined constitute, in effect, an electromagnetic recorder. The receiver 46 serves to permit the operator to hear the telephone conversation which is being recorded. The receiver 47 may, in the main, be of usual construction, and, as shown, comprises the usual magnet 48 and vibratory diaphragm 49. A neck 50 formed on the receiver passes over

the recorder neck 2', as shown in Figs. 1 and 2, so that vibrations corresponding to those set up by the diaphragm 49 may be conveyed to the recorder stylus 2'.

In order to insure the maximum compactness possible for my improved apparatus, I preferably form the box or container 34 with a recessed portion 51 in which the receiver 46 is adapted to be supported, as by the lever 52 pivoted at 53 to a lug 54 threaded loosely into one of the side walls of the recess 51. Two of the walls of the said recess are shown at 51' and 51" in Fig. 3. The lever 52 has a substantially horizontal portion 55 having a hook shaped end 56 adapted to be passed through an eye 57 secured to the top of the receiver 46 to thereby support the said receiver. The lower end of the lever 52 is provided with an opening 58 through which a pin 59 secured to the side of the casing 34 passes loosely, this pin serving normally to prevent movement of lever 52 laterally, that is, about the axis of the threaded portion of lug 54. A stop 60 slidably mounted, as by a collar 61, upon the lever 52 above the pivot 53 serves, when in the position shown in Fig. 2, to limit the movement of the upper end of the lever 52 towards the container 34 so as to prevent the movement of the lower end of lever 52 outwardly out of operative relation to the pin 59. The collar 61 may be retained in position upon the lever 52 by friction or in any other suitable manner. By raising stop 60 above the top of cabinet 34, the lower end of lever 52 may be moved outwardly of the cabinet beyond the pin 59, and the said lever may then be rotated laterally so as to move the upper end thereof below the top of the cabinet and into the recess 51. The apparatus is thus arranged in a very compact and convenient form for shipment. From this compact form, the lever 52 and stop 60 may again be readily moved back into the position shown in Fig. 2.

The cabinet or container 34 comprises the box-like upper portion 34' hingedly connected to a flat bottom member 34", as shown at 62, a spring clasp 63 secured to the bottom member 34" being provided with an opening adapted to receive a pin 64 secured to the upper portion 34' to thereby normally hold the container in closed position. By moving the upper end of the spring catch 63 away from the upper portion 34' of the container and out of engagement with the pin 64, the upper portion of the container may be readily raised so as to permit access to the interior thereof. Referring to Fig. 3, it will be seen that the container provides a space for the reception of a cell or battery 65 or other suitable source of electrical energy. The terminals of the battery, as shown in Figs. 2 and 3, are in the form of spring contacts 66 and 67, these contacts, 130

as shown in Fig. 3, being preferably secured to the top of the battery 65. The wall 51' of the container 34 has secured to the bottom thereof, as by screws, one of which is indicated in dotted lines at 68, a flat support 69 formed of electrical insulation and having secured thereto two contacts 70 and 71 respectively. The contacts 70 and 71 are arranged to engage the contacts 67 and 66 respectively.

The electrical circuits for the battery 65, the transmitter 39, and the receivers 46 and 47 comprise a wire or other suitable conductor 72 leading from the contact 71 and electrically connected to a spring contact 73 arranged adjacent to but normally out of contact with the upturned end 74 of the contact 75. The contacts 73 and 75 are secured to the under side of the top wall of the container 34 and are held out of electrical connection with each other and with the container 34 by spacing blocks 76 and 77 of electrical insulation. On the contact 73 adjacent one extremity thereof rests a headed pin 78, of electrical insulation, the upper portion of which is adapted to be engaged and pressed downwardly by the bead 33' on the telephone receiver 33 when the latter is placed in position upon the clasp formed by the supporting arms 35. This downward movement of the pin 78 forces the free end of the contact 73 into engagement with the upturned portion 74 of the contact 75 so as to establish electrical connection between the said contacts. When the receiver 33 is lifted from the clasp formed by the arms 35, the free end of the contact 73 rises by reason of its resiliency and thereby breaks the electrical connection between the contacts 73 and 75. From the contact 75 there leads a conductor 79 which is electrically connected with one of the electrodes of the transmitter 39. The other electrode of the said transmitter is electrically connected to a conductor 80 which is in electrical connection with two conductors 81 and 82, so as to form a divided circuit, the conductor 81 being in one branch of the circuit and leading to the receiver 46 and the conductor 82 being in the other branch of the circuit and leading to the receiver 47. From the receiver 46 leads a conductor 83 which, as shown, is connected to the contact 70. From the receiver 47 leads a conductor 84 which is in electrical connection with the spring contact 85, one end of which is secured to the insulating support 69, the other end of said contact being normally free and spaced from the upturned end 86 of the contact 70. I provide the operating means for the pump 19 with means for forcing the contact 85 into engagement with the part 86 when the said pump is operated to move the clutch 12 into operative position, the said forcing means permitting the contact 85 to

become disengaged from the part 86 when the pump 19 is operated in the reverse direction. The means shown for this purpose comprise a rock arm 87 pivoted within the cabinet 34, as by a pivot 88 secured to the inside of the container 34, for movement about a horizontal axis, the said arm carrying at its lower end a disc 89 of electrical insulation adapted to coact with the inclined or cam-like portion 90 of the contact 85 to move the same towards the part 86 of the contact 70. The arm 87 is connected to the piston 91 of the pump 19 by a link 92 which has a pivotal connection with the piston 91 and a slotted connection with the arm 87, the said slotted connection being similar to the connection 25, 26 for the pump 17. The arm 87 has lateral extensions 93 and 94 to which are pivotally connected push buttons 95 and 96 extending slidably through openings in the top of the container 34 to permit ready manual operation of the pump 19 and the clutch mechanism controlled thereby, while simultaneously forcing contact 85 into engagement with contact 70. The contact 70, as hereinbefore stated, is in contact with the spring contact 67 which is connected to one of the terminals of the battery 65. It will be seen that the conductor 81, the receiver 46, and the conductor 83 form a shunt from the conductor 80 to the contact 70 in the main circuit containing the battery 65, the transmitter 39, and the recorder 47, 2. The circuit containing the receiver 46 should be of very high resistance compared with the circuit containing the receiver 47, so that the undulations impressed on the receiver 47 will be sufficiently strong to cause a good distinct record to be made into the record medium 6 while the sound waves set up by the receiver 46 will not be objectionably or unnecessarily intense. The resistances may, for example, be about 650 ohms for the circuit containing the receiver 46 and about 15 ohms for the circuit containing the receiver 47. This result may be obtained by making the receiver 46 of suitable high resistance and the receiver 47 of suitable low resistance or it may be accomplished in any suitable way whereby the said shunt containing the receiver 46 has a suitably higher electrical resistance than the portion of the said main circuit between the conductor 80 and contact 70. The sound wave impulses or undulations from the receiver 33, which are too weak to permit a satisfactory phonograph or sound record to be made thereby, are amplified or intensified through the transmitter 39 by reason of the comparatively strong current in the circuit containing the said transmitter and the recorder 47, 2, and are thus impressed upon the said recorder through the circuit connections between said transmitter and recorder with sufficient intensity to permit a good distinct record to

be made upon the cylinder 6. In order to insure the removal of the telephone receiver 33 from its supporting clasp on the container 34 and its replacement upon the hook 31' of the telephone standard when the operator is finished with the use of my improved apparatus, I provide a signal which is in operation as long as the receiver 33 is in operative position upon the container 34 and the receiver 46 hung up on the hook 56. As shown, the signal consists of an electric buzzer 97, but various other kinds of signals may be employed. The electric buzzer or bell 97, as shown, has its terminals connected with conductors 98 and 99, the former conductor being electrically connected with the conductor 79 at the point 100. The conductor 99 is in electrical connection with a spring contact 101 which has an end portion 102 directed towards the free end of a spring contact 103, the contacts 101 and 103 being connected adjacent one end to the inside of one of the side walls of the container 34 and being normally held out of electrical engagement with each other by spacing members 104 and 105 of electrical insulation. The free end of the contact 103 bears against one end of a pin 106, formed of electrical insulation, the pin 106 being 30 slidable within an opening in the wall of the container 34 and having its end remote from that which engages the contact 103 in engagement with the lower end of the lever 52; so that when the receiver 46 is placed 35 upon the hook 56, the weight of said receiver will cause the lever 52 to move in an anti-clockwise direction and thereby force the pin 106 to the right, referring to Fig. 2, whereby the contact 103 is moved into electrical 40 connection with the end 102 of the contact 101. When the receiver 46 is raised from the hook 56, the spring contact 103 moves by reason of its resiliency out of engagement with the end 102 of the contact 101 45 and at the same time forces the pin 106 and the lower end of lever 52 to the left, referring to Fig. 2 into the positions shown in said figure. The contact 103 is electrically connected to the conductor 83, as by a conductor 107. It will be seen that so long as the receiver 46 is supported by the hook 56 and the receiver 33 is in operative position upon the container 34, the contact 103 will engage the end 102 of the contact 101 and 50 the contact 73 will engage the end 74 of the contact 75; so that there will be a complete circuit from the battery 65 through the contacts 66 and 71, the conductor 72, the contacts 73 and 75, the conductor 79 to the 55 point 100 and thence through the conductor 98, the signal 97, the conductor 99, the contacts 101 and 103, the conductor 107, the conductor 83 and the contacts 70 and 67 back to the battery 65, and the signal 97 will be 60 in operation. As it is customary and natu-

ral for the operator as soon as he has finished with the use of the receiver 46 to hang the same upon the hook 56, the signal 97 will be thrown into operation after the use of the apparatus is finished unless the receiver 33 70 is removed from its support upon the container 34. With this signal in operation, the operator is apprised of the fact that he has failed to replace the receiver 33 upon the receiver hook 31'; and thus the danger of leaving the receiver 33 off the hook 31' for long periods is avoided. 75

Most of the electrical connections hereinbefore described are located within the container 34. The portions of the conductors 80 81 and 83 which are connected to the receiver 46 and must necessarily extend without the casing 34, are, as shown in Fig. 1, enclosed within a suitable insulating cord 108. Each of the conductors 82 and 84 connected 85 to the electromagnetic recorder 47, 2 is preferably formed in two sections detachably connected by a suitable connecting device 109. The portions of the conductors 82 and 84 without the cabinet 34 are preferably enclosed within an insulating cord 110, as 90 shown in Fig. 1.

In operation, the receiver 47 is placed over the neck 2' of the recorder 2, the tube 20 being likewise connected with the tubular 95 members 21 and 22. When the operator receives a call on the telephone 31, he places the receiver 33 in operative position upon the clasp formed by the arms 35 and applies the receiver 46 to his ear, at the same time 100 making certain that the button 95 is depressed so that the contact 85 will be in electrical connection with the portion 86 of the contact 70 and so that the clutch 12 will be thrown into operative position to cause 105 the rotation of the record cylinder 6. The placing of the receiver 33 in operative position upon the top of the container 34 causes the contact 73 to be moved into engagement with the end 74 of the contact 75, as herein- 110 before described. The phonograph now operates in the usual manner, the record cylinder being rotated and the recorder 2 being moved along the record cylinder by the feeding means 8 and 9 in the usual manner. 115 When the diaphragm 33² of the receiver 33 is set into vibration in accordance with the telephone conversation of the party speaking to the operator of the device herein described, undulations or impulses corresponding to the vibrations of the said diaphragm are conveyed by the air in the connection 37 to the transmitter diaphragm, and impulses or undulations corresponding with those imparted to the diaphragm 40 are impressed 120 upon the circuit including the transmitter 39, conductors 80 and 82, the receiver 47, the conductor 84, the contacts 85 and 70, the battery 65, the contacts 66 and 71, the conductor 72, the contacts 73 and 75, and the conductor 125 130

79. The receiver 47 will thereby be caused to operate the recorder 2 to cause a record of the telephone message received to be recorded upon the cylinder 6. At the same time, 5 the transmitter 39 will cause the impulses or undulations corresponding to the vibrations of the diaphragm 40 to be impressed upon the circuit comprising the transmitter 39, the conductor 80, conductor 81, the receiver 46, the conductor 83, the contacts 70 and 67, the battery 65, the contacts 66 and 71, the conductor 72, the contacts 73 and 75, and the conductor 79, so that the telephone message transmitted over the line containing the receiver 33 will be distinctly heard by the operator when he applies receiver 46 to his ear. In ordinary telephones in common use, the sound waves uttered into the mouthpiece of telephone receiver 32 cause 20 the receiver 33 of the same apparatus to be set into operation and are audible through the said receiver. The message or the sounds uttered by the operator of my herein described device are accordingly recorded 25 upon the cylinder 6 in the same manner as the sounds uttered over the telephone line to the said operator. As long as the receiver 46 is removed from the hook 56 and in use by the operator, the contacts 101 and 103 30 will be spaced from each other so that the signal 97 will be out of operation. As soon as the matter to be recorded is completed, the operator hangs the receiver 46 upon the hook 56 and the circuit through the signal 35 97 will be closed until the receiver 33 is removed from its operative position upon the container 34. The signal 97 warns the operator to place the receiver 33 back upon the telephone hook 31'. The removal of the 40 receiver 33 from its operative position on the container 34 causes the spring contact 73 to automatically move out of engagement with the end 74 of the contact 75. When the telephone conversation or the other sounds uttered over the telephone are completely recorded, the button 96 should be depressed so as to move the clutch 12 into inoperative 45 position and to permit the contact 85 to move out of engagement with the contact 70. 50 The function of the contacts 85 and 70 is primarily to ensure the opening of the circuit containing the receiver 47 and the battery 65 when the apparatus is not in operation to thereby avoid the waste of current. 55 The device shown is capable of being modified in many ways without departing from the spirit of my invention, and I wish it to be understood, therefore, that I am not limited to the exact details shown and described. 60 What I claim as new and desire to protect by Letters Patent of the United States is as follows:

1. The combination with an amplifying electric circuit containing a source of current supply, a telephone transmitter, and an

electro-magnetic recorder, of means whereby a telephone receiver may be supported in position to impress on said transmitter undulations corresponding to sound waves, and a branch circuit connected to said first 70 named circuit and containing a telephone receiver, substantially as described.

2. An electric circuit containing a source of current supply and a telephone transmitter, said circuit having a portion containing 75 a recorder, and a shunt around said portion including a telephone receiver, said shunt being of at least twenty-five times the resistance of said portion, substantially as described. 80

3. The combination with an electric circuit containing a source of current supply, a telephone transmitter, and a recorder, of means whereby a telephone receiver may be supported in position to impress on said 85 transmitter undulations corresponding to sound waves, and a branch circuit connected to said first named circuit and containing a telephone receiver, substantially as described. 90

4. The combination with an electric circuit containing a source of current supply and a telephone transmitter, and means whereby a telephone receiver may be supported in position to impress on said transmitter undulations corresponding to sound waves, of means for automatically controlling the closing and opening of said circuit by placing the telephone receiver in operative position with respect to said transmitter or removing the same therefrom, sub- 100 substantially as described. 95

5. The combination with an electric circuit containing a telephone transmitter, a source of current supply, and a recorder, of means whereby a telephone receiver may be supported in position to impress on said transmitter undulations corresponding to sound waves, a branch circuit connected to said first named circuit and containing a telephone receiver, and means for controlling 105 the closing and opening of said first named circuit by placing the first named telephone receiver in said position or removing the same therefrom, substantially as described. 110

6. The combination with an electric circuit containing a source of current supply, a telephone transmitter, a recorder, and means for forming a gap in said circuit, of phonograph mechanism coacting with said recorder, means whereby a telephone receiver 115 may be supported in position to impress on said transmitter undulations corresponding to sound waves, and unitary means for effecting the closing of said gap and controlling the operation of said mechanism, sub- 120 substantially as described. 125

7. The combination with an electric circuit containing a source of current supply, a telephone transmitter, a recorder, and means for forming a gap in said circuit, of means 130

whereby a telephone receiver may be supported in position to impress on said transmitter undulations corresponding to sound waves, a rotatable record support in operative relation to said recorder, and unitary controlling means for effecting the closing of said gap and the rotation of said record support, substantially as described.

8. The combination with an electric circuit containing a telephone transmitter, a source of current supply, and a recorder, of means whereby a telephone receiver may be supported in position to impress on said transmitter undulations corresponding to sound waves, a branch circuit connected to said first named circuit and containing a telephone receiver, means for controlling the closing and opening of said first named circuit by placing said first named telephone receiver in said position or removing the same therefrom, a rotatable record support in operative relation to said recorder, and unitary controlling means for effecting the rotation of said record support and the closing of a gap in said first named circuit, substantially as described.

9. A container for a source of electrical energy, a telephone transmitter carried by said container, means whereby the said source may be electrically connected to said transmitter, controlling means carried by said container for causing a gap to be formed or closed in said connecting means, a rotatable support, and starting and stopping means for said support connected to and operable by said controlling means, substantially as described.

10. A container, a telephone transmitter carried thereby, electrically conductive means connected to said transmitter, controlling means carried by said container for causing a gap to be formed or closed in said conductive means, a rotatable support, and starting and stopping means for said support connected to and operable by said controlling means, substantially as described.

11. The combination of means operable by a telephone receiver for recording undulations corresponding to sound waves, said recording means being provided with means for supporting the telephone receiver in operative relation thereto, and signal means for indicating when the receiver is in operative relation to said recording means, substantially as described.

12. The combination of means operable by a telephone receiver for recording undulations corresponding to sound waves, said recording means being provided with means for supporting the telephone receiver in operative relation thereto, signal means for indicating when the receiver is in operative relation to said recording means, and supporting means operable by the weight of the article supported thereby to control the opera-

tion of said signal means, substantially as described.

13. The combination of means for recording undulations corresponding to sound waves, a telephone receiver operatively connected to said means, signal means, and supporting means for said receiver operable by the weight thereof to control the operation of said signal means, substantially as described. 75

14. The combination of means operable by a telephone receiver for recording undulations corresponding to sound waves, said recording means being provided with means for supporting the telephone receiver in operative relation, signal means for indicating when the receiver is in operative relation to said recording means, a second telephone receiver arranged to be operated to set up sound wave undulations corresponding to those set up by said first telephone receiver, and supporting means for said second telephone receiver operable by the weight thereof to control the operation of said signal means, substantially as described. 80 90

15. The combination with an electric circuit containing a source of current supply, a telephone transmitter, and a phonographic recorder, of means whereby a telephone receiver may be supported in position to impress on said transmitter undulations corresponding to sound waves, and a telephone receiver electrically connected in circuit with said transmitter, substantially as described. 95

16. In an apparatus of the class described, the combination of a phonographic recording mechanism including a record medium, a diaphragm, a stylus mounted on said diaphragm, an electric device for vibrating said diaphragm, an electric circuit including said device, telephone mechanism comprising a receiver and a transmitter connected to said circuit, means whereby said transmitter may be used independently of said receiver to operate said electric device, and means for supplying current to said circuit. 100 105 110

17. The combination with an electric circuit containing a source of current supply, a telephone transmitter, and a recorder, of phonograph mechanism coacting with said recorder, means whereby a telephone receiver may be supported in position to impress on said transmitter undulations corresponding to sound waves, and unitary means for controlling the opening and closing of said circuit and the operation of said mechanism, substantially as described. 115 120

18. The combination of a telephone receiver, a pair of contacts, and supporting means for said receiver normally occupying an operative position relative to said contacts in which it is movable to control the engagement and disengagement of said contacts, said supporting means being mounted for movement to another position in which 125 130

it is in inoperative relation to said contacts, substantially as described.

19. The combination of a telephone receiver, a pair of contacts, a supporting lever for said receiver normally occupying an operative position relative to said contacts in which it is movable to control the engagement and disengagement of such contacts, said lever being mounted for movement to another position in which it is in inoperative relation to said contacts, and means for normally preventing said movement of the lever, including a member adjustable to permit such movement thereof, substantially as described.

20. The combination of a telephone line comprising a receiver, an electric circuit containing a source of current supply, a tele-

phone transmitter and a phonographic recorder, means whereby said telephone receiver may be removably supported in operative position with respect to said transmitter to impress thereon undulations corresponding to sound waves, and supplementary receiving means so arranged and positioned that it may be used for hearing the messages coming in over the telephone line when the said receiver is supported in operative position with respect to said transmitter, substantially as described.

This specification signed and witnessed this 25th day of November, 1914.
